202,991

COMBINED GOLF BALL DISPENSER AND TEE HOLDER

Robert T. Carlson, 4821 N. Kildare Ave., Chicago, Ill.

Filed Dec. 9, 1964, Ser. No. 82,971

Term of patent 14 years

(Cl. D34—5)

The broken line representations of golf balls and tees in the several views are for purposes of illustration only.

I claim:

The ornamental design for a combined golf ball dispenser and the holder, as shown and described.
